UNITED STATES PATENT OFFICE.

CHARLES DAVID BONSALL, OF NEW KENSINGTON, PENNSYLVANIA, ASSIGNOR TO UNION METAL PRODUCTS COMPANY, OF CHICAGO, ILLINOIS, A CORPORATION OF DELAWARE.

DEVICE FOR OPERATING CAR COUPLERS.

Original application filed October 24, 1924, Serial No. 745,635. Divided and this application filed April 13, 1925. Serial No. 22,668.

This particular invention relates to what is generally known in the art as a rotating type of uncoupling device for car couplers and comprises an operating rod revolvably mounted on the car with brackets or in any other convenient manner, which rod is usually bent downwardly at the outer end to form a handle, and is bent outwardly at its inner end to form a crank, projecting over the coupler, which crank is provided with a horizontally positioned eye with its axis perpendicular to the longitudinal center of the car. The standard vertical plane coupler has a knuckle pivoted to the coupler head and provided with a tail behind which the lock is placed. The lock lifter protrudes through and above the coupler head and is provided with a horizontally positioned eye. This lock lifter eye is $1\frac{1}{16}$ " in diameter and its axis is perpendicular to the longitudinal center of the car. This size and position has been determined by the American Railroad Association and is standard for the majority of couplers now in service.

My invention resides in the connection between the eye on the crank of the operating rod and the eye on the coupler lock lifter. When the handle is raised the rod is revolved and the crank is thereby raised which unlocks the coupler by raising the lock lifter.

The coupler moves backwardly and forwardly longitudinally of the car in buffing and draft and also moves sidewise in rounding curves, etc., and the connection between the coupler and the operating rod must permit such movements without the component parts becoming disengaged from each other or from either the coupler or the operating rod. It is frequently necessary to uncouple cars when they are coupled together and in contact so that it is impossible to throw the knuckle of either coupler. To meet this condition couplers are designed to assume a "lock set position" wherein the lock lifter can be raised from behind the tail of the knuckle and retained in such a position by means within the head of the coupler independent of the operating rod. This allows the operating rod to fall close to the lock lifter. To accommodate such a movement the connection between the operating rod crank and the coupler must fore-shorten, which is accomplished by making it of sev-

eral parts which collapse by means of a hinge joint or a sliding connection to each other, or, as in my design, the component parts are pivotally and slidably connected. The operating rod, as above described, is old and in use on hundreds of thousands of cars now in existence. Such rods had a short chain connecting the crank arm to the lock lifter of the coupler which chains proved unsatisfactory and were responsible for a little more than half of the defects for uncoupling mechanisms reported by the Interstate Commerce Commission. These chains were defective because they were broken, missing, kinked and either too long or too short.

One of the objects of this invention is to provide a connection between the rod and the coupler which will eliminate the defects of the old chain and meet all service conditions required.

These short chains were broken by falling behind the coupler horn and being smashed between the coupler horn and the striking casting by impact of the cars in coupling. The device is designed so that the component parts cannot become disconnected from each other or from the operating rod or the coupler. The connection between the component parts and also their connections to the operating rod and the coupler are such that the device cannot become "kinked". Formerly when a brakeman wanted a small chain to repair one of the old connections he simply guessed as to the amount of chain required and applied it to the car, which accounts for the number of "too long" and "too short" chains reported by the commission. This is not possible with my device.

Another object is to provide a connection which may be hooked into the eye of the coupler lock lifter with the hooked member connected to the crank of the operating rod by another member which permits it to adapt itself to the various service movements of the coupler but prevents it from becoming disengaged from the lock lifter in service.

Another object of the invention is to provide a device wherein the component parts are identical and duplicates, therefore, interchangeable. Duplication, of course, also simplifies manufacture, handling, accounting, etc.

Another object of the invention is to provide a device which can be assembled at the point of manufacture and shipped as a unit to the point of application to a car and which can be applied to the car by a very simple operation which requires no special tools or appliances.

Another object is to obtain a device wherein the component parts are duplicates so that they cannot be wrongfully applied to the car or to each other.

In the drawings:

Fig. 1 is a perspective view of a portion of a car with my invention applied thereon.

Fig. 2 is an elevation of the connector.

Fig. 3 is a side view of Fig. 2.

Fig. 4 is an elevation of modification of Figs. 2 and 3 with a slidable connection.

Fig. 5 is a side view of Fig. 4.

Fig. 6 is a pair of members per Figs. 4 and 5 in assembled open position.

Fig. 7 is the modification per Figs. 4 and 5 in partially collapsed position and also shows the slidable connection between the pairs of members.

Fig. 8 is a modification wherein the axes of the eyes of the connector are perpendicular to the axes of the pivots (or pivot).

Fig. 9 is a side view of Fig. 8.

Fig. 10 is a pair of members per Figs. 8 and 9 in assembled open position.

In a railway car the operating rod 1 is mounted on the end still 2 by brackets 3. The usual operating rod had a handle 4 and a crank arm 5 which arm has a horizontally disposed eye 6. The lock lifter 7 of the coupler 8 also has a horizontally disposed eye 9 and my invention resides in a connector for these two mentioned eyes.

The device comprises two pairs of complementary hooked and preferably duplicate members. The members of each pair are shaped to be positioned opposite each other to form a closed eye.

The pairs of members are pivoted together by a separate means (20) than the means (21) which connect the two pairs of members together. The connection 21 performs the further function of retaining the members in the position forming a closed eye. In this construction shown in Figs. 2 and 3 the members are provided with round holes so that the pairs of members are pivoted together, while in Figs. 4 to 7, inclusive, the members are provided with elongated holes 27 so that the pairs of members are slidably, as well as, pivotally connected together. Figs. 6 and 7 show how the component parts collapse and slide relative to each other so that the connection may accommodate service conditions.

The pairs of members are opened up scissor fashion, as shown in Figs. 6 (and 10) for connection to the crank arm 5 and lock lifter 7, respectively, and then both

pairs are moved to closed position, (see Figs. 2 and 4) and then connected together by pivot 21 which is held in place by nuts 22. The device is shipped from the factory, as shown in Fig. 6, and it will be noted that the upper assembled pair of members is a duplicate of the lower assembled pair.

The construction shown in Figs. 8, 9 and 10 is like Figs. 4 to 7 inclusive, except that the axes of the closed eyes (23—24) are perpendicular to the axis of the pivot 25 instead of parallel therewith. The hinge or pivot action of the two arrangements are in vertical planes at right angles to each other.

This construction may be provided with a slotted hole (26), as shown, or a round hole, as shown in Fig. 2.

All four component parts are preferably identical.

This is a division of my co-pending application Serial No. 745,635, filed October 24, 1924.

I claim:

1. A connector for a railway car coupler and its operating rod, comprising two pairs of complementary members, each pair of complementary members pivotally connected to move opposite each other to form a closed eye, and separate means to pivotally connect said pairs of members.

2. A connector for a railway car coupler and its operating rod, comprising two pairs of complementary members, each pair of complementary members pivotally connected to move opposite each other to from a closed eye, and separate means to slidably connect said pairs of members.

3. A connector for a railway car coupler and its operating rod, comprising two pairs of complementary members, each pair of complementary members pivotally connected to move opposite each other to form a closed eye and separate means to pivotally and slidably connect said pairs of members.

4. A connector for a railway car coupler and its operating rod, comprising two pairs of members, each member having a hook at one end and a hole at its opposite end, each pair comprising two such members independently pivotally connected to move opposite each other to form closed eyes at the opposite end of the connector, a pin rotatively engaging all of said holes, and means to hold said pin in place.

5. A connector for a railway car coupler and its operating rod, comprising two pairs of members, each member having a hook at one end and an elongated hole at its opposite end, each pair comprising two such members independently pivotally connected to move opposite each other to form closed eyes at the opposite ends of the connector, a pin rotatively engaging all of said holes, and means to hold said pin in place.

6. A connector for a railway car coupler

and its operating rod, comprising two duplicate pairs of members, each member having a hook at one end and an elongated hole at its opposite end, each pair comprising two such members independently pivotally connected to move opposite each other to form closed eyes at the opposite end of the connector, a pin rotatively engaging all of said holes, and means to hold said pin in place.

- 10 7. A connector for a railway car coupler and its operating rod, comprising two pairs of complementary members, each pair of complementary members pivotally connected to move opposite each other to form a closed eye, and separate means to pivotally connect said pairs of members, said means also retaining said members in the position forming closed eyes.

8. A connector for a railway car coupler and its operating rod, comprising four identical members, which are secured together to form two pairs of complementary members, each pair of complementary members pivotally connected to move opposite each other to form a closed eye, and separate means to connect said pairs of members.

9. A connector for a railway car coupler and its operating rod, comprising four identical members, which are secured together to form two pairs of complementary members, each pair of complementary members pivotally connected to move opposite each other to form a closed eye, and separate means to connect said pairs of members, which means also retains said members in the position forming closed eyes.

10. A connector for a railway car coupler and its operating rod, comprising two pairs of complementary members, each pair of complementary members pivotally connected to move opposite each other to form a closed eye, and a separate pivot having its axis normal to the axes of the closed eyes pivotally connecting said pairs of members.

- 45 11. A connector for a railway car coupler

and its operating rod, comprising two pairs of complementary members, each pair of complementary members pivotally connected to move opposite each other to form a closed eye, and a separate pivot having its axis normal to the axes of the closed eyes slidably connecting said pairs of members.

12. A connector for a railway car coupler and its operating rod, comprising two pairs of complementary members, each pair of complementary members pivotally connected to move opposite each other to form a closed eye, and a separate pivot having its axis normal to the axes of the closed eyes pivotally connecting said pairs of members, said pivot also retaining said members in the position forming closed eyes.

13. In a railway car, the combination of an operating rod mounted upon the car having a horizontally disposed eye, a coupler with a lock lifter having a horizontally disposed eye, a connector therefor comprising two pairs of complementary members, each pair of complementary members pivotally connected to move opposite each other to form a closed eye, and a separate pivot connecting said pairs of members, said closed eyes forming engagements to the lock lifter eye and operating rod eye, respectively.

14. In a railway car, the combination of an operating rod mounted upon the car having a horizontally disposed eye, a coupler with a lock lifter having a horizontally disposed eye, a connector therefor comprising two pairs of complementary members, each pair of complementary members pivotally connected to move opposite each other to form a closed eye, and a separate pivot having its axis normal to the axes of the closed eyes connecting said pairs of members, said closed eyes forming engagements to the lock lifter eye and operating rod eye, respectively.

CHARLES DAVID BONSALL.
